(57) CLAIM

What is claimed is the ornamental design for a remote activation padlock with window, as shown and described.

DESCRIPTION

FIG. 1 is a front elevation view showing the remote activation padlock with window of applicant's invention in an open position, the back being a mirror image thereof.

FIG. 2 is a side elevation of the remote activation padlock with window of applicant's invention, both sides being identical.

FIG. 3 is a top elevation of the remote activation padlock with window of applicant's invention, both sides being identical.

FIG. 4 is a bottom elevation of the remote activation padlock with window of applicant's invention; and,

FIG. 5 is a front perspective of the remote activation padlock with window of applicant's invention in a closed position.
